Primary Examiner — Karen S Acker*Assistant Examiner* — Andrea Marie McKay(74) Attorney, Agent, or Firm — Nitin Kaushik(57) CLAIM

The ornamental design for an LED light, as shown and described.

DESCRIPTION

FIG. 1 is a front perspective view of an LED light, showing my new design;

FIG. 2 is a rear perspective view thereof;

FIG. 3 is a front view thereof; and,

FIG. 4 is a rear view thereof.

The dashed broken lines depict portions of the LED light that form no part of the claim.

DESCRIPTIONFIG. 1

The ornamental design for an LED light, as shown and described.

FIG. 2

The ornamental design for an LED light, as shown and described.

FIG. 3

The ornamental design for an LED light, as shown and described.

FIG. 4

The ornamental design for an LED light, as shown and described.

The LED light includes symbolic breaks along its length. The areas between the break lines form no part of the claimed design.

1 Claim, 4 Drawing Sheets
